DESIGN FOR A COMBINED ELECTRIC PUSH BUTTON AND ESCUTCHEON PLATE

Malcolm I. Davis, New Haven, Conn., assignor to
The Ansonia Electrical Company, Ansonia,
Conn., a corporation of Connecticut

Application March 22, 1939, Serial No. 83,776

Term of patent 14 years

To all whom it may concern:

Be it known that I, Malcolm I. Davis, a citizen of the United States, residing at New Haven, in the county of New Haven and State of Connecticut, have invented a new, original, and ornamental Design for a Combined Electric Push Button and Escutcheon Plate, of which the following is a specification, reference being had to the accompanying drawing, forming part thereof.

Fig. 1 is a perspective view of a combined electric push button and escutcheon plate showing my new design;

Fig. 2 is a face view thereof; and

Fig. 3 is a side view thereof.

I claim:

The ornamental design for a combined electric push button and escutcheon plate, substantially as shown.

MALCOLM I. DAVIS.
